UNITED STATES PATENT OFFICE.

PETER A. OSHANYK, OF WILTON, NORTH DAKOTA.

DOOR-OPENING MECHANISM.

1,408,628.

Specification of Letters Patent.

Patented Mar. 7, 1922.

Application filed January 24, 1921. Serial No. 439,627.

To all whom it may concern:

Be it known that I, PETER A. OSHANYK, a citizen of the United States, and a resident of Wilton, county of Burleigh and State of North Dakota, have invented certain new and useful Improvements in Door-Opening Mechanisms; and I do hereby declare that the following is a full, clear, and exact description of the invention such as will enable others skilled in the art to which it appertains to make and use the same.

This invention relates to improvements in door opening mechanisms, and has for an object to provide a mechanism of such character, particularly adaptable for the opening of the sliding doors of garages and like structures, whereby when a vehicle is to be driven into a garage so equipped and is in proximity to the doors thereof, these doors will be caused to automatically open and then close subsequently to entrance of the vehicle.

Another object of the invention is to provide a mechanism of the character mentioned including a novel and simple arrangement of levers for transmitting the initial motion imparted to the doors in such a manner as to slide said doors in opposite directions to their respective open positions, and later returning them to their normal arrangement, and during such return, effecting the sliding of the doors to their respective closed positions.

Other objects will be in part obvious and in part pointed out hereinafter.

In order that the invention and its mode of operation may be readily understood by persons skilled in the art, I have in the accompanying drawings and in the following detailed description thereof, set out one embodiment of the same.

In these drawings,

Figure 1 is a front elevation of a garage, the sliding doors of which are equipped with my improved door-opening mechanism, a part of the doors and housing structure being broken away and shown in section;

Figure 2 is a fragmentary vertical section taken on the line 2-2 of Figure 1;

Figure 3 is a horizontal section taken on the line 3-3 of Figure 1; and

Figure 4 is a reduced fragmentary detail in section showing the relative arrangement of the levers of the opening mechanism when in actuated positions.

Having more particular reference to the

drawings in connection with which like characters of reference will designate corresponding parts throughout the several views, 1 represents a garage equipped with a pair 60 of oppositely disposed slidable doors 2. Flushly arranged in a pit or pocket formed partly within the garage and partly without the same, is a substantially rectangular housing 3 which serves as means for receiving 65 the various levers of my improved door-opening mechanism, and also as means for receiving in the open upper end thereof, a pair of oppositely inclined platforms designated by the reference characters 4 and 4'. 70 In this connection, it is to be noted that stops or rests 5 are secured to the inner sides of the opposite end walls of the housing 3, and receive thereon, at times, adjacent portions of the platforms 4 and 4', the remaining extremities of these platforms being received on the opposite sides of the track 6 arranged in the housing and disposed transversely thereof intermediate said end walls; this arrangement being clearly shown in the 80 Figure 4. In addition to affording means for receiving the adjacent extremities of the several platforms 4 and 4', the track 6, obviously, also affords means for receiving the roller bearings 7 of the several slidable doors 85 2, in order that the same may be freely moved.

Positioned on the bottom of the housing 3 and disposed transversely of the same directly beneath the transverse track 6, is a 90 bar 8 having its opposite ends curved upwardly as at 9 and provided with bracketed extremities 10 which are attached to the door frame structure 11 of the garage 1, and thus serve to brace the same as well as the body 95 portion of the bar and its curved extremities 9. Pintles 12 are secured to and extend laterally from the upper sides of each of the curved ends 9, and serve to pivotally mount operating levers 13 on the bar 8 at distances 100 sufficiently above the same to permit of free pivotal movement of said levers. The lower portions of each of these levers 13 are reversely curved as at 14 and provided with inturned slotted extensions 15, which in turn 105 have loose pivotal connection with bell crank levers 16 mounted on brackets 17 in the bottom of the housing 3; the free extremities of each of these bell crank levers being interconnected by means of the contractile coil 110 spring 18, whose function is to normally maintain said levers, together with the levers

13, in their respective closed or initial positions.

As means for transmitting the necessary motion to the operating levers 13 whereby 5 to effect sliding of the particular doors 2 connected thereto, to open and closed positions, levers 19 and 19' are pivoted to the under sides of the several platforms 4 and 4', preferably at points in proximity to the 10 outer marginal portions thereof, as shown in the Figures 2 and 4, said levers being mounted in suitable bearings on brackets 20 secured to adjacent portions of the housing 3, while the hereinbefore mentioned pivotal 15 connection of the same with the platforms 4 and 4' is effected through the medium of transverse bars 21 extending across the under sides of the platforms 4 and 4' in proximity to the outer marginal portions thereof; there being levers 19 and 19' pivotally 20 connected to the opposite extremities of each of said bars, as shown in the Figure 3. The inner ends of the levers 19 and 19' are slotted and have loose pivotal connection as at 25 22, while other levers 23 are pivotally connected at 24 to the levers 19 and 19' and have mounting in brackets 25, also secured to adjacent portions of the housing 3, the remaining ends of said levers 23 being pivoted to the opposite extremities of arms 26 30 secured to and extending transversely to the under sides of the platforms 4 and 4' in a manner corresponding to the arrangement of the bars 21.

35 In order to brace the side portions of the housing 3, and to render the same sufficiently rigid to withstand stress imparted thereto by passage of vehicles into and out of the garage so equipped, I may and preferably do arrange diagonal braces 27 longitudinally of the housing and in proximity to said opposite sides, offsetting the extremities of the same and securing them as at 28 to adjacent portions of said housing sides, 45 while the intermediate portions are secured at 29 to parts of the transverse bar 8.

The operation of my improved door-opening mechanism may be described as follows:

A vehicle to be driven into or housed by 50 the garage 1 is directed onto the front platform 4', whereupon the weight of said vehicle will effect downward movement of the platform 4', which in turn will force the outer ends of the levers 19' downwardly 55 and the inner end upwardly. By reason of the upward movement of the inner ends of these levers 19', contact between the same and the inwardly extending ends 15 of the operating levers 13 will be effected and a 60 resultant forward thrust imparted to each of the same. Because of the fact that the levers 13 have pivotal mounting on the curved ends 9 of the bar 8, it will be appreciated that such upward thrusts will cause the 65 remaining ends thereof to be swung out-

wardly, and since these remaining ends have pivotal connection as at 30 with their respective doors 2, said doors will be immediately slid in opposite directions to their open positions. The vehicle upon entering 70 the garage 1 will travel over the remaining platform 4, and by consequence, will cause the doors 2 to be maintained in their opened positions. However, when the platform 4 is relieved of the weight of the vehicle, a contractile coil spring 18, which has been previously placed under tension by the opening of the doors 2, will promptly act to draw the bell crank levers 16 to their normal positions, and by reason of such action, will impart pivotal motion to the operating levers 13 in a direction opposite to that first explained, and thus slide the doors 2 in opposite directions to their respective closed positions. 85

It may be here noted that due to the provision of the levers 23, the several platforms 4 and 4', when subjected to the weight of a vehicle or other object arranged thereon, will be prevented from tilting with relation 90 to the adjacent portions of the housing 3, and also will provide a comparatively substantial support for the vehicle or other object thereon without effecting detrimental results to the remaining levers of which the 95 improved opening mechanism is comprised.

Manifestly, the construction shown is capable of considerable modification, and such modification as is within the scope of my claims, I consider within the spirit of 100 my invention.

I claim:

1. In combination with the oppositely disposed slideable doors of a building, a housing mounted flushly with respect to the flooring of said building, partly within and partly without the same, opposed vertically movable platforms arranged over the open upper portions of the housing, longitudinal levers mounted on the opposite sides of the 105 housing pivotally connected at their opposite ends to portions of said platforms and having their inner ends pivotally interconnected, vertical levers mounted transversely in the housing having pivotal connection at 110 their upper ends with said doors and their free ends arranged in horizontal planes in the path of movement of the inner portions of said first levers, and spring means connected to said transverse levers for normally maintaining the same in their inward positions. 115

2. In combination with the oppositely disposed slideable doors of a building, a housing arranged flushly with the flooring thereof, partly within and partly without the same, vertically movable platforms arranged in the upper portion of said housing, means for limiting downward movement of the 125 platforms, longitudinal levers mounted on 130

the opposite sides of the housing and having pivotal connection at their opposite ends with portions of the platforms, vertical levers mounted transversely in the housing 5 having the lower portions thereof bent laterally and inwardly and disposed in the path of travel of the inner portions of said first levers, and means for normally maintaining all of said levers in and returning 10 the same to their initial positions.

3. In combination with the oppositely disposed slidable doors of a building, a housing arranged flushly with the flooring thereof, partly within and partly without the 15 same, vertically movable platforms positioned adjacent the open upper portions of the housing, a bar disposed transversely of the housing bottom and arranged intermediate the opposite end walls of the same, 20 having brackets on its opposite ends, vertical transversely movable levers pivoted to the brackets on the opposite ends of said bar having pivotal connection at their upper

ends with the doors, the lower portions of said levers being bent inwardly and laterally, 25 bell crank levers mounted in the housing having pivotal connection with the adjacent ends of said inwardly and laterally bent portions of the vertical levers, spring means interconnecting said bell crank levers, longitudinal levers mounted on the opposite sides of the housing having pivotal connection at their outer ends with adjacent portions of the platforms and their remaining ends pivotally interconnected and disposed for imparting motion to the inwardly and laterally bent portions of the vertical levers adjacent thereto, and other levers mounted on the opposite sides of the housing having certain of their ends pivoted to said longitudinal 40 levers and their remaining ends pivoted to the inner portions of said platforms.

In witness whereof I have hereunto set my hand.

PETER A. OSHANYK.
